RADIANT HEAT SUPERHEATER

Charles E. Lucke, New York, N. Y., assignor to
The Babcock & Wilcox Company, Bayonne,
N. J., a Corporation of New Jersey

Application September 28, 1929
Serial No. 395,868

16 Claims. (Cl. 122—481)

This invention relates to a novel and improved radiant heat superheater, or the like, and the novel features will be best understood from the following description and the accompanying drawings, in which I have shown selected embodiments of the invention, and in which—

Fig. 1 is a vertical sectional view through the lower portion of a furnace wall and boiler showing one form of the invention;
10 Fig. 2 is a fragmentary view similar to Fig. 1, but showing a different embodiment of the invention;

Fig. 3 is a view taken on the line 3—3 of Fig. 2;
15 Fig. 4 is a fragmentary rear view of some of the tubes appearing in Fig. 3, but drawn on an enlarged scale.

Fig. 5 is a view on the line 5—5 of Fig. 4 and of Fig. 3;

Fig. 6 is a view on the line 6—6 of Fig. 4;
20 Figs. 7, 8 and 9 are views corresponding to Figs. 4, 5 and 6, respectively, but showing a different form of guiding means for the tubes;

Figs. 10, 11 and 12 are other views corresponding to Figs. 4, 5 and 6, but showing a third form 25 of guiding means.

Referring first to Fig. 1, the invention is shown as embodied in a superheater disposed in a furnace wall adjoining a combustion chamber 1 disposed beneath a boiler, some of the tubes of which 30 are indicated at 2. It will be understood that the use of the invention is not restricted to a boiler furnace, as the superheater may be installed as a separately fired radiant heat superheater or the like. The tubes of the superheater 35 are indicated at 3 and their upper ends 4 are bent outwardly away from the furnace and extend outside the wall where they enter holes in a header 5. The outwardly bent ends are clamped between a stationary member 6 and a removable member 7, 40 suitable bolts 8 being used for this purpose. This clamping means is better shown in Fig. 3. The lower ends 9 of the tubes are also bent outwardly and joined to a header 10. These ends 9 are similarly secured between a stationary clamping 45 member 11 and a removable clamping member 12, by bolts 13. The headers 5 and 10 rest on supporting blocks 15 which are secured to structural members 14. Preferably, the clamps are tightened to such an extent as to prevent their 50 movement under expansion and contraction, and any movement beyond the clamps is provided for by the blocks 15, upon which the headers may slide.

In the form shown in Fig. 1, the tubes are provided adjacent the ends 4 and 9, with curved

portions 16 joined by a reversed curve 17, so that tubes may freely expand and contract under the influence of the heat of the furnace to which they are subjected. Flexible insulating material 18 may be provided on the backs or outer sides of the tubes.

In the form shown in Fig. 2, the parts are generally similar and similar reference characters apply to both. In this form, however, the tubes 3 are formed in a curve extending inwardly toward the furnace so that expansion will take place in that direction rather than outwardly away from the furnace, as in the form shown in Fig. 1. Both forms, however, will be seen to provide free and unrestrained expansion and contraction for the tubes intermediate their ends, while the ends of the tubes are held against movement in fixed supports independent of the headers. The form shown in Fig. 2 however is considered preferable for installations in which high furnace temperatures are present. The clamps are protected by suitable refractory material 19 against the action of the heat of the furnace.

Preferably, the tubes are provided with means which will limit the transverse displacement of one tube with respect to an adjacent tube, without interrupting the continuity of the wall formed by the tubes while, at the same time, permitting free flexing of the wall. This may be achieved in different ways, some of which are illustrated in Figs. 4 to 12, inclusive. In each case, the means employed is a guiding means, which allows a limited amount of displacement of one tube with respect to an adjacent tube.

Referring first to Figs. 4, 5 and 6, in which is shown the means appearing in Fig. 3, this means comprises lugs 20 welded to the tubes and preferably at intervals along their lengths, a pair of lugs being provided on one tube to receive between them a lug on an adjacent tube. By this arrangement, it will be obvious that, while a tube may bow under the influence of heat, nevertheless it will be maintained as part of a continuous wall formed by the tubes. At the same time, it will be obvious that the tubes at different parts of this wall may bow substantially different amounts without being restrained to any substantial degree in so doing.

In Figs. 7, 8 and 9, is shown another way in which the same result may be obtained. In this form rearwardly extending lugs 21 are provided, these lugs being welded to the sides of adjacent tubes and being provided with vertically extending tongues 22 between which and the tubes are disposed clips 23.

105

110

In Figs. 10, 11 and 12, the same result is obtained by welding lugs 24 to the tubes and by disposing between these lugs a T-shaped member 25, the head of which rests upon the top of the lugs 24, while its web 26 is received therebetween.

In all the forms shown it will be seen that substantially free expansion and contraction is possible at any point of the curved wall surface 10 formed by the tubes. Ordinarily any condition in a furnace which would affect one tube would similarly affect adjoining tubes so that tubes at any point in the wall would act substantially the same. However, in the length of a wall occupied by a superheater, or the like, conditions may be varied considerably, but the conditions will vary more or less gradually and it will be seen that the above constructions all permit tubes in different parts of the wall to assume different 20 positions with respect to the normal position shown. In this way the curvature of the wall surface may change with temperature changes and unequal degrees of curvature are permitted from side to side of the wall without interrupting its continuity. The arrangements therefor are very flexible, permitting transverse movement of the tubes due to expansion and contraction and such change between adjacent tubes, both transverse and longitudinal, as may be 25 necessary to meet local conditions in the furnace.

I claim:—

1. In a furnace wall, a row of tubes subjected to the heat of the furnace, having their opposite ends extending outwardly from the furnace, headers connected to the tube ends, and means independent of the headers for holding the tubes in fixed position at points adjacent their ends, the tubes intermediate said points being disposed on a flat curve extending substantially 35 from one of said points to the other and exposed to radiant heat from the furnace to permit expansion and contraction thereof.

2. In a furnace wall, a row of tubes subjected to the heat of the furnace, having their opposite 40 ends extending outwardly from the furnace, headers connected to the tube ends, means independent of the headers for holding the tubes in fixed position at points adjacent their ends, the tubes intermediate said points being disposed 45 on a flat curve extending substantially from one of said points to the other and exposed to radiant heat from the furnace to permit expansion and contraction thereof, and means holding each tube in approximately constant relation to adjacent joining tubes.

3. In a furnace wall, a row of tubes subjected to the heat of the furnace, having their opposite ends extending outwardly from the furnace, headers connected to the tube ends, means independent of the headers for holding the tubes in fixed position at points adjacent their ends, the tubes intermediate said points being disposed 60 on a flat curve extending substantially from one of said points to the other and exposed to radiant heat from the furnace to permit expansion and contraction thereof, and means maintaining said tubes in position in the row.

4. In a furnace wall, a row of tubes subjected to the heat of the furnace, having their opposite 70 ends extending outwardly from the furnace, headers connected to the tube ends, means independent of the headers for holding the tubes in fixed position at points adjacent their ends, the tubes intermediate said points being disposed 75 on a flat curve extending substantially from one of

said points to the other and exposed to radiant heat from the furnace to permit expansion and contraction thereof, and refractory material disposed between said holding means and the furnace.

80

5. In a furnace wall, a row of tubes subjected to the heat of the furnace and having their opposite ends extending outwardly from the furnace, headers connected to the tube ends, means supporting said headers, and clamps engaging opposite sides of said outwardly extending ends and holding them in fixed position, the tubes intermediate said clamps being unsupported and curved to permit expansion and contraction thereof.

85

6. In a furnace wall, a row of tubes subjected to the heat of the furnace and having their opposite ends extending outwardly from the furnace, headers connected to the tube ends, means supporting said headers and permitting movement thereof due to expansion and contraction of said tubes, and clamps engaging opposite sides of said outwardly extending ends and holding them in fixed position, the tubes intermediate said clamps being unsupported and curved to 100 permit expansion and contraction thereof.

95

7. A radiantly heated steam superheater comprising, in combination with a furnace, a row of single loop steam conducting tubes constituting the structural support of a curved furnace wall 105 through which the furnace gases cannot pass, an outlet header connected to the outlet ends of the tubes and positioned externally of the furnace, and an inlet header connected to the inlet ends of the tubes and positioned externally of the furnace, the wall of tubes being bowed mainly in a single bend extending substantially from one end of the wall to the other so that all intermediate portions of the wall are free to move laterally under the influence of temperature changes.

110

8. A radiant superheater for steam power systems comprising, in combination with a furnace including a combustion chamber, an outside wall of the combustion chamber, a row of steam conducting superheater tubes forming the structural support of the wall, and superheater inlet and outlet headers outside the combustion chamber and connected respectively to the inlet and outlet ends of the tubes, the tubes being bowed inwardly of the furnace in a single bend or loop so as to prevent disruption of the wall by expansion and contraction, intermediate portions of the wall being free to move in the direction of a normal to the wall without disturbing the closures at the wall ends.

115

9. A furnace having a flexible external wall section continuously bowed inwardly of the furnace and consisting of a layer of flexible heat insulating material as a backing for a row of curved superheating tubes conveying steam to 135 be radiantly heated.

120

10. A radiantly heated steam superheater comprising, in combination with a furnace, a row of loop steam conducting tubes constituting the structural support of a furnace wall section 140 through which the furnace gases cannot pass, an outlet header connected to the outlet ends of the tubes and positioned externally of the furnace, and an inlet header connected to the inlet ends of the tubes and positioned externally of the furnace, the wall of tubes being bowed so that all intermediate portions of the wall are free to move laterally under the influence of temperature changes.

125

11. An outside furnace wall, a supporting struc-

130

140

145

150

ture therefor, the said supporting structure consisting of a row of radiant heat absorbing tubes forming a steam superheating surface and having continuously curved intermediate portion substantially free to expand and contract inwardly of the furnace while maintaining the wall structure as a complete furnace wall, and means for fixedly supporting the tubes at their ends.

12. A radiant superheater for steam power system comprising, in combination with a furnace including a combustion chamber, an outside wall section constituting a part of a wall of the combustion chamber, a row of steam conducting superheater tubes forming the structural support of the section, heat resisting material adjacent the tubes, and superheater inlet and outlet headers outside the combustion chamber and connected respectively to the inlet and outlet ends of the tubes, the tubes being bowed inwardly of the furnace in a bend or loop so as to prevent disruption of the section by expansion and contraction, intermediate portions of the section being free to move in the direction of a normal to the wall without disturbing the closures at the wall ends.

13. A radiantly heated superheater comprising, in combination with a furnace, a row of looped fluid conducting tubes constituting the structural support of a furnace wall section through which the furnace gases cannot pass, and an outlet chamber connected to the outlet ends of the tubes, the wall of tubes being bowed so that all intermediate portions of the wall are free to move laterally under the influence of temperature changes.

14. In a furnace having enclosing walls, a radiant heat superheater comprising a row of steam superheating tubes arranged at the inner side of one of said walls, each of said tubes having spaced end portions and an intermediate portion connecting said end portions and exposed

to the radiant heat of said furnace, said end portions being fixed in position and said exposed intermediate portion being shaped in a continuous convex curve extending inwardly of said furnace, whereby said curved intermediate tube portions will tend to expand and contract in their general initial form under the influence of furnace temperature changes.

15. In a furnace having enclosing walls, a radiant heat superheater comprising a row of steam superheating tubes lining the inner side of one of said walls, each of said tubes having spaced end portions and an intermediate portion connecting said end portions and exposed to the radiant heat of said furnace, said end portions being fixed in position and said exposed intermediate portion being shaped in a continuous convex curve of a relatively large radius and extending inwardly of said furnace, whereby said curved intermediate tube portions will tend to expand and contract in their general initial form under the influence of furnace temperature changes.

16. In a furnace having enclosing walls, a radiant heat superheater comprising a row of closely spaced steam superheating tubes arranged at the inner side of one of said walls, each of said tubes having spaced end portions and an intermediate portion connecting said end portions and exposed to the radiant heat of said furnace, means fixing said end portions in position, said exposed intermediate portion being shaped in a single continuous convex curve of a relatively large radius and extending inwardly of said furnace, whereby said curved intermediate tube portions will tend to expand and contract in their general initial form under the influence of furnace temperature changes, and means limiting relative movement of the intermediate portions of adjacent tubes.
